UNITED STATES PATENT OFFICE

WILFRED ERNEST PRIESTLEY, OF SEATTLE, WASHINGTON

PACKET OF FIRECRACKERS WITH SEALED BAND

Application filed December 11, 1929. Serial No. 413,248.

This invention relates to the process or method of packing firecrackers, and to the packages packed thereby.

Heretofore firecrackers have been held together in packages by the plaiting or twisting together of the fuses thereof, and thereby difficulty has been caused in the segregation of the units when the same were desired to be fired separately, and many of the fuses were pulled from the firecrackers in the removal, or delay created by the careful disentanglement of the fuses. Again when it was desired to fire the entire package at one time, the result has been that many of the separate firecrackers were scattered by the explosion of others or their fuses pulled out without becoming ignited, and in all such cases the explosions of the several firecrackers were intermittent and the time of discharge so delayed that the package, if thrown into the air, would have fallen to the ground before many of the firecrackers would have become discharged.

And it is one of the objects of this invention to pack and provide a package of firecrackers which may be used without any of the said disadvantages.

A further object is to provide a process and method of packing firecrackers, so that each unit may be quickly removed by the operator for firing without injury to any other unit, and also to so provide that the entire pack may be fired simultaneously, without damage to any unit or failure of any to explode.

A still further object is to provide such process method and pack, whereby opposite rows of firecrackers will be held together by a band pasted over the abutting ends of the firecrackers in the opposing rows whereby the rows will be held at a fixed distance from each other, with an enclosed passageway or channel formed between the rows and between the bands on opposite sides of the opposing ends, and the fuses of all the firecrackers be bent at right angles therewith and trained along and within the channel adjacent each other, but not otherwise attached together, to provide for the easy removal of any unit by raising the cover band over the channel, and also provide for igniting all the firecrackers by the rapid spread

of the fire from one to the other after one fuse has been lighted.

With these and other objects I have illustrated my invention by the accompanying drawings, of which:

Figure 1 represents a front elevation of the complete packet of firecrackers, with a part of the wrapper and part of the band both broken away to show the parts;

Figure 2 represents a top plan, in section taken on line 2—2 of Figure 1;

Figure 3 is a detail, showing two firecracker units abutting each other with the fuses thereof bent preparatory to assembling in a pack;

Figure 4 represents a detail showing a number of the units assembled in juxtaposition with the fuses pressed between the ends ready for the binding band thereover; and

Figure 5 represents a cross section view of the upper part of Figure 1 taken on line 5 thereof.

Like numerals on the different figures represent like parts.

Numerical 6 represents a unit or a single firecracker of any size or variety, and 7 represents the usual fuse extending therefrom for ignition thereof. 8 represents my band or ribbon, for holding the units together in the desired positions and for forming a channel or tunnel for the aggregated fuses for ignition. This band or ribbon is preferably of paper or other suitable material of sufficient strength to hold the units together in a pack, and yet be sufficiently pliable for removal by the operator when he may desire to remove any one or more of the units. I place a coating of suitable adhesive, indicated by dotted lines as 10, on one side, or face of this band, and then place the two rows of the firecrackers opposite to each other with the fuse ends abutting, bend all of the fuses at right angles with the units, and preferably in one direction, then press the two rows together against the massed fuses between. I then place the band parallel over the space or channel marked 12, occupied by the fuses and seal the edges of the band a suitable width on and over the opposing end portions of all the firecrackers by means of the

adhesive, the band being on both sides of the firecrackers, so that the channel containing the fuses is enclosed by the ends of the two rows of the units and by the extension of the band over and between the said ends, and space between. However the fuses from the two last units at one end of the pack, I bring out from the channel as indicated by numeral 11, for ready lighting by a match or other means, in case it is desired to fire the entire package together.

The adhesive may be made from flour paste or similar materials which when dried after affixing to the units and band, will harden and have sufficient strength to hold the bands and units in the package form for transportation, but which adhesive may be easily broken without injury to the units when the operator desires to remove any thereof, and to so do, he peels off one of the bands a given distance and readily removes any one or more units for separate firing, and no damage is done to the fuses by the removal as they are unattached. In event that any of the fuses should adhere to the paste, the outer layer of the fuse being of thin tissue paper readily tears off without injury to the remainder of the fuse.

Where it is desired to fire the entire pack, the operator ignites the projecting fuses 11, and deposits the pack on the ground or projects the same into the air, meanwhile the exposed fuse burns as a slow match without danger to the operator, but as soon as the fire reaches the entrance of the channel or tunnel the fire speeds through the entire tunnel practically instantaneously, as the compacted fuses in the tunnel act as a piped quick match in the confined space, and all of the fuses are thereby ignited, and mostly burned up to the ends of the firecrackers, and the gases from burning fuses break off the units simultaneously from the bands and scatter the units while simultaneously bursting. When this occurs in the air, a beautiful fiery cascade is displayed, and no undischarged units remain.

The band is preferably of bright colors or may carry stars or other characters printed for ornamental purposes thereon. For transportation an outer envelope or casing is provided which may be bright colored or be transparent, or otherwise made ornamental.

I am aware that loose strips or bands have been used for wrappers on packages of firecrackers for holding the same together for transportation; but such loose bands or wrappers required that the firecracker units have their fuses entwined to prevent lateral movements and to hold the package in shape, but this method was productive of much injury in the pulling of the fuses from the units either in transportation or in the division of the units for separate firing, and such packs

when ignited as a whole, failed to provide a satisfactory spectacle as the units when ignited at all, exploded in a desultory manner, and a great many of the units failed to ignite by reason of the fuses having been withdrawn, or from being ejected from the pack by prior units exploding. In order to overcome such difficulties I made extensive experiments in the United States and particularly in firecracker factories in Taiwan, and finally discovered thereby that by the application of a suitable band affixed to the units as herein described, that the units were held together without the entwining of the fuses, and that the units could also be easily separated manually when desired, and that when the pack was ignited as a body that the explosion of all the units took place practically simultaneously.

Having described my invention, I claim as new for Letters Patent:

1. In a packet of firecrackers, comprising two rows of firecrackers with the fuse ends thereof abutting each other, an adhesive band sealed to the abutting ends parallel with the space occupied by the fuses between the ends and over the space, to form an enclosed channel with the fuses therein between the ends.

2. That improvement in packets of firecrackers, which comprises firecrackers in oppositely positioned parallel rows with the fuse ends abutting each other and projecting fuses at right angles with the units, the rows divided by a space sufficient to hold the assembled fuses therein, a band with an adhesive on one side thereof, and binding the oppositely positioned rows of units together with the adhesive band attached over the ends of the units on the outsides thereof parallel over the space between the units, to normally hold the units together in a pack, and provide an enclosed air channel between the ends of the units with the fuses parallel therein, for igniting all the units collectively.

3. A packet of firecrackers with parallel rows of firecrackers held together with the fuse ends abutting, an adhesive band pasted to and over the end portions of the sides of the units, the rows of units spaced apart sufficient to encase the fuses of the units, the fuses from the units at one end of the pack extending from the space, and the remainder of the fuses placed parallel with each other in the channel in close juxtaposition between the ends of the units and between the bands, for the synchronous ignition of all the units.

4. A packet of firecrackers, comprising rows of firecrackers arranged with their fuse ends confronting in close juxtaposition, and a band pasted to and over the adjacent ends of said rows of firecrackers, uniting said rows into a packet, and forming with the confronting ends of said firecrackers an enclosed channel for the fuses.

5. A packet of firecrackers comprising

rows of firecrackers arranged with their fuse ends confronting in close juxtaposition, and a band pasted to and over the adjacent ends of said rows of firecrackers, uniting said rows into a packet and forming with the confronting ends of said firecrackers an enclosed channel for the fuses, the latter being freely arranged in said channel.

5 In testimony whereof I affix my signature.
10 WILFRED ERNEST PRIESTLEY.
